REFRIGERATING APPARATUS

Herman J. Dick and Robert E. Fleming, Dayton,
Ohio, assignors to General Motors Corporation,
Dayton, Ohio, a corporation of Delaware

Application January 30, 1937, Serial No. 123,242

13 Claims. (Cl. 62—101)

This invention relates to refrigerator cabinets and particularly to that type wherein bottled beverages can be cooled in a liquid bath.

Beverage coolers, as heretofore constructed, have been subject to various objections and disadvantages. This is particularly true of those types wherein an open top tank is used as the storage compartment which is partially filled with a heat exchange medium, such as water.

In order to provide a more satisfactory beverage cooler, it is an object of our invention to provide a beverage cooler wherein a small and compact cooling coil and a water bath agitating means can be placed in the storage compartment in an inconspicuous manner as a unit assembly and wherein the cooling coil thereof can be connected to a refrigerant circulating means prior to the time of installation so that the same can be readily installed or removed from the cooler without disconnecting the refrigerant lines.

It is a further object of our invention to provide a bottled beverage cooler wherein an agitating means, for circulating the water bath, can be located adjacent a refrigerating coil, both being positioned within the storage compartment, and the agitating means can be driven by means of a refrigerant liquefying unit connected to the refrigerating coil, in such a manner that the coil may be installed and removed independently of the driving connection for the agitating means.

Further objects and advantages of the present invention will be apparent from the following description, reference being had to the accompanying drawings wherein a preferred form of the invention is clearly shown.

In the drawings:

Fig. 1 is a top view of the beverage cooler with parts broken away to show the cooling coil;

Fig. 2 is a rear elevational view of the bottle cooler;

Fig. 3 is a transverse cross-sectional view of the beverage cooler taken on the line 3—3 of Fig. 1;

Fig. 4 is an enlarged cross-sectional view of the cooling unit and agitating means shown in Fig. 3 to more clearly show the structure thereof;

Fig. 5 is a vertical cross-sectional view showing the manner in which the agitator driving means is connected to the refrigerant liquefying unit; and

Fig. 6 is a vertical cross-sectional view taken on line 6—6 of Fig. 1.

In our invention, we provide a cabinet structure 10 which is divided into two compartments. An upper compartment 11 is provided for the storage of bottled beverages, and a compartment

12 is positioned below compartment 11 wherein a refrigerant liquefying unit may be placed. The storage compartment 11 consists of a tank 13 which is provided with suitably insulated side walls 14, and an insulated bottom wall 15. A liquid 9 is provided within the tank 13 as a heat transfer fluid for cooling the bottled beverages stored therein. A removable top member 16, having an insulated wall 16a, is provided whereby access may be gained to the storage compartment 11. The top 16 is divided into two parts and is provided with hinges 17 along the transverse center line thereof, so that either half of the top 16 may be raised at will without necessitating removal of the entire member. A rubber gasket 18 is provided between a flange 19 on the top 16 and the top wall of the cabinet 10. The gasket is retained in position by means of screws 20 and secured thereby to the top wall of the cabinet 10. Suitable side wall panels 21 are provided for sealing the insulation 14 on the side walls of the cabinet 10 and a panel 23 is provided for sealing the bottom wall insulation 15. The end wall panels 22 of cabinet 10 extend below the bottom wall 15 of the cabinet and provide the end walls of the machinery compartment 12. The side walls of the machinery compartment 12 consist of panels 24 having louvers 25 through which air can be circulated.

A cooling coil 30 is provided within the storage compartment 11 and is connected to a refrigerant liquefying unit 31 by means of conduits 32 and 33. Liquid refrigerant is supplied to the cooling coil 30 by means of the conduit 33 from a liquid expansion device 34. The liquid expansion device 35 may be of any suitable type, such as a high side float operated valve, the structure of which is well known in the patented art, for controlling the flow of liquid refrigerant to the cooling coil 30. The cooling coil 30 is provided with a header 35 wherein the expanded refrigerant from the coil 30 collects. The gaseous refrigerant is withdrawn from the header 35 through the conduit 32 by means of a compressor 36. The compressor is driven by means of a motor 37. Belts 38 are provided as the driving connection between the pulley 39 mounted on the motor and the flywheel 40 which is mounted on the compressor. The compressor 36 compresses the expanded gas and delivers same to a condenser 41 where the refrigerant is liquefied in the well known manner. The motor 37 is controlled by means of a control switch 42, preferably of a snap acting type, many of which are disclosed in the patented art. The control switch 42 is connected to a bulb 43

by means of a conduit 44, said bulb being positioned within the water bath of the storage compartment 11. The control element 42 will be responsive to pressure differentials created within the bulb 43, thereby causing the refrigerant liquefying unit to start and stop in response to the temperature of the water bath in the storage compartment 11.

The cooling unit for maintaining a constant temperature within the water bath in the storage compartment and means for circulating said water bath consists of a tubular casing member 50 which is provided with a plurality of perforations 51. A cap 51a is placed over the tube 50 to prevent articles from being dropped into the tube. The cooling coil 30 consists of a tube wound in a substantially cylindrical structure and is secured to the casing member 50 in any suitable manner, such as by spot soldering the tubes to the casing 50. The casing 50 is secured to a cylindrical base 52 by means of screws 53. The base 52 is substantially of a spider-like structure having openings 54 therein, and legs 54a. The central portion 55 of the base 52 is provided with an extended shaft 56 which extends through a tubular member 57 positioned in the bottom wall 15 of the storage compartment 11. The tubular member 57, provided in the wall 15, has an extended flange 58 on the upper end thereof. The bottom wall 59 of the tank 13 is provided with a depression 60 having an inwardly extending flange 61. The members 56 and 57 extend through an opening 62 provided in the flange 61. Gasket members 63 and 64 are provided on opposite sides of the flange 61. A nut 65 is provided on a threaded portion 66 of member 57 for compressing the gaskets 63 and 64 against the flange 61 and between flange 58 and nut 65. This structure thereby provides a fluid tight joint around the opening 62 in the bottom wall of the tank member 13. The end portion 56a of the extension 56 is threaded to receive a nut 67. The nut is threaded against the bottom end of member 57 causing the extension 56 to be drawn downwardly, thereby compressing a gasket 68 between the central portion 55 of the base 52 and the flange 58 of member 57 to provide a fluid tight joint.

A tubular member 70 is recessed in the central portion 55 of the base 52 and is secured thereto by means of sweat soldering. The tubular member 70 extends upwardly to near the top of the casing 50. An insert 71, provided in the tube 70, is adapted to provide a bearing for the shaft 72. The shaft 72 extends vertically within the tube 70 and has its lower end bearinged in the extension 56. Stops 72a are provided on the shaft 72 to limit the vertical movement thereof. A cap 73 is placed on the upper end of the shaft 72 and is secured thereto by means of a set screw 74. A tube 75 is sweat soldered, or otherwise secured, to the lower end of the cap 73 and extends downwardly around the tube 70 to near the bottom of the casing 50. A fan 76 is secured, in a horizontal position, to the lower end of the tube 75. This fan is for the purpose of causing circulation of the water in the storage compartment 11. The water is drawn into the casing 50 below the base 52 and is circulated vertically therethrough. The water will pass through the cooling coil 30 and discharge from the casing 50 through the openings 51.

The means for driving the circulating fan 76 consists of a flexible cable connection 80, one end of which is secured to the lower end of the

shaft 72 and the opposite end of the cable is connected to the hub 81 of the flywheel of the compressor 36. The cable consists of a flexible driving member 82 surrounded by a flexible casing 83. The ends of the cable 82 are provided with square-shaped ends 84 and 85. The end 85 of the cable extends into a square opening 86 provided in the lower end of the shaft 72 and the end 84 extends into a square opening 87 provided in an adaptor fitting 88 which is threaded upon the threaded portion 89 of the compressor flywheel hub 81. One end of the flexible casing 83, surrounding the cable 82, is secured by means of an adaptor fitting 91 to the threaded portion 56a of the extension 56 and the opposite end of the casing is secured by means of an adaptor fitting 90 to an upright member 92. The upright member 92 is rigidly secured in any suitable manner to the high side float 34.

The cooling coil, of the combined cooling and agitator unit, is to be connected to the refrigerant liquefying unit, by the interconnecting conduits prior to the time of installation of the equipment in the beverage cooler. To provide for this installation of the cooling coil in the storage compartment 11, it is necessary that some provision be made whereby the refrigerant lines from the refrigerant liquefying unit to the cooling coil can be removably positioned within a wall of the beverage cooler. We have provided this means by placing a groove 100 in the top edge of the rear wall 101 of the storage compartment. The liquid refrigerant line 33, the gaseous refrigerant line 32, and the conduit connecting the control bulb 43 with switch 42 can rise vertically from the machinery compartment 12 and along the rear wall 101 to the top thereof. The conduits can then pass horizontally through the groove 100 and thence into the storage compartment 11. The gasket 18 upon which the flange 19 of the top 40 16 is adapted to seal will pass over the top of the conduits 32, 33 and 44 respectively, thereby providing a continuous seal for the top 16. The extension 56 is placed through the bottom wall 15 of the storage compartment, the nut 67 retaining the cooling and agitating assembly in position.

Up to this time, the driving connection between the agitator and the refrigerant liquefying unit has not been made. But with the cooling 50 and agitating assembly in position in the storage compartment and upon the refrigerant liquefying unit being placed in position in the machinery compartment, the driving connection therebetween can now be made. The ends of the flexible drive shaft are placed in their respective positions in the end of the shaft 72 and the fitting 88, on the hub of the compressor flywheel 40, and are retained in place by means of the adaptor fittings 90 and 91. The ends of the stationary 60 casing 83 are also retained in position by the adaptor fittings 90 and 91. A rubber covering member 95 is provided for enclosing the adaptor fitting 91 and the end of the casing 83 associated therewith to prevent condensation of moisture 65 thereon.

While the form of embodiment of the present invention as herein disclosed constitutes a preferred form, it is to be understood that other forms might be adopted, all coming within the 70 scope of the claims which follow.

What is claimed is as follows:

1. Refrigerating apparatus, including an insulated enclosure containing a liquid heat transfer bath and articles to be cooled immersed 75

therein, an evaporating means positioned for absorbing heat from the liquid bath, a refrigerant liquefying means for supplying liquid refrigerant to and for withdrawing expanded refrigerant from the evaporating means, agitating means positioned adjacent said evaporating means, said agitating means extending through the bottom wall of the insulated enclosure, and means operatively connecting the agitating means to the refrigerant liquefying means for driving said agitating means.

2. Refrigerating apparatus, including an insulated enclosure containing a liquid heat transfer bath and articles to be cooled immersed therein, an evaporating means comprising a tubular member submerged in the bath, a refrigerant liquefying means for supplying liquid refrigerant to and for withdrawing expanded refrigerant from said evaporating means, refrigerant conduits for connecting said evaporating means and said refrigerant liquefying means, said conduits extending exteriorly of said enclosure near the top wall thereof, agitating means positioned within the confines of the evaporating means, said agitating means having a drive shaft extending exteriorly of said enclosure, and means operatively connecting the agitating means to the refrigerant liquefying means for driving said agitating means.

3. Refrigerating apparatus, including an insulated enclosure containing a liquid heat transfer bath and articles to be cooled immersed therein, an evaporating means comprising a tubular member submerged in the bath, a refrigerant liquefying means for supplying liquid refrigerant to and for withdrawing expanded refrigerant from said evaporating means, refrigerant circulating conduits for connecting said evaporating means and said refrigerant liquefying means, a thermal element positioned within the insulated enclosure, a control element positioned exteriorly of said insulated enclosure operatively connected by a conduit to said thermal element, said refrigerant circulating conduits and said control element conduit extending exteriorly of the insulated enclosure near the top wall thereof, agitating means positioned within the confines of the evaporating means, said agitating means having a drive shaft extending exteriorly of said enclosure, and means operatively connecting the agitating means to the refrigerant liquefying means.

4. Refrigerating apparatus, including an insulated enclosure containing a liquid heat transfer bath and articles to be cooled immersed therein, an evaporating means positioned for absorbing heat from the liquid bath, a refrigerant liquefying means for supplying liquid refrigerant to and for withdrawing expanded refrigerant from the evaporating means, refrigerant conduits for connecting said evaporating means and said refrigerant liquefying means, said conduits extending exteriorly of said enclosure near the top wall thereof, agitating means positioned adjacent said evaporating means, said agitating means extending through the bottom wall of the insulated enclosure, and means operatively connecting the agitating means to the refrigerant liquefying means for driving said agitating means.

5. Refrigerating apparatus, including an insulated enclosure containing a liquid heat transfer bath and articles to be cooled immersed therein, an evaporating means comprising a coil of tubing supported by a tubular shell, said evapo-

rator and shell being positioned for absorbing heat from the liquid bath, a refrigerant liquefying means for supplying liquid refrigerant to and for withdrawing expanded refrigerant from the evaporating means, agitating means positioned adjacent said evaporating means, said agitating means extending through the bottom wall of the insulated enclosure, and means operatively connecting the agitating means to the refrigerant liquefying means for driving said agitating means.

6. Refrigerating apparatus, including an insulated enclosure containing a liquid heat transfer bath and articles to be cooled immersed therein, an evaporating means comprising a tubular member submerged in the bath, a refrigerant liquefying means for supplying liquid refrigerant to and for withdrawing expanded refrigerant from said evaporating means, refrigerant conduits for connecting said evaporating means and said refrigerant liquefying means, said conduits extending exteriorly of said enclosure near the top wall thereof, agitating means positioned centrally within the evaporating means, said agitating means having a drive shaft extending through the bottom wall of the insulated enclosure, and means operatively connecting the agitating means to the refrigerant liquefying means for driving said agitating means.

7. Refrigerating apparatus, including an insulated enclosure containing a liquid heat transfer bath and articles to be cooled immersed therein, an evaporating means comprising a tubular member submerged in the bath, a refrigerant liquefying means for supplying liquid refrigerant to and for withdrawing expanded refrigerant from said evaporating means, refrigerant conduits for connecting said evaporating means and said refrigerant liquefying means, said conduits extending exteriorly of said enclosure near the top wall thereof, agitating means positioned centrally within the evaporating means, said agitating means having a drive shaft extending through the bottom wall of the insulated enclosure, and flexible driving means operatively connecting the agitating means to the refrigerant liquefying means for rotating said agitating means.

8. Refrigerating apparatus, including an insulated enclosure containing a liquid heat transfer bath and articles to be cooled immersed therein, an evaporating means comprising a tubular member submerged in the bath, a refrigerant liquefying means for supplying liquid refrigerant to and for withdrawing expanded refrigerant from said evaporating means, refrigerant conduits for connecting said evaporating means and said refrigerant liquefying means, said conduits extending exteriorly of said enclosure near the top wall thereof, agitating means positioned centrally within the evaporating means, said agitating means having a drive shaft extending through the bottom wall of the insulated enclosure, and flexible driving means operatively connecting the agitating means to the flywheel of the compressor of the refrigerant liquefying means.

9. Refrigerating apparatus, including an insulated enclosure containing a liquid heat transfer bath, evaporating means positioned for absorbing heat from the liquid bath, refrigerant liquefying means for supplying liquid refrigerant to and for withdrawing gaseous refrigerant from the evaporating means, refrigerant conduits, said conduits extending from said evaporating means and passing over the top edge of a side wall of said enclosure and connected to said refrigerant liquefy-

ing means, agitating means positioned adjacent said evaporating means, said agitating means extending through the bottom wall of the insulated enclosure, and means operatively connecting the agitating means to the refrigerant liquefying means.

10. A bottle cooling cabinet comprising an insulated tank containing a liquid heat transfer bath, a machinery compartment positioned below said tank, evaporating means positioned within said tank, refrigerant liquefying means positioned in said machinery compartment, refrigerant conduits, said conduits extending from said evaporating means and passing over the top edge of a side 15 wall of said tank and connected to said refrigerant liquefying means, agitating means positioned adjacent said evaporating means, said agitating means extending through the bottom wall of the insulated enclosure, and means operatively connecting the agitating means to the refrigerant liquefying means.

11. Refrigerating apparatus, including an insulated enclosure containing a liquid heat transfer bath and articles to be cooled immersed therein, 25 a cooling means positioned for absorbing heat from the liquid bath, a refrigerant circulating means for supplying refrigerant to and for withdrawing refrigerant from the cooling means, agitating means positioned adjacent said cooling 30 means, said agitating means extending through the bottom wall of the insulated enclosure, and

means operatively connecting the agitating means to the refrigerant circulating means for driving said agitating means.

12. Refrigerating apparatus, including an insulated enclosure containing a liquid heat transfer bath, cooling means positioned for absorbing heat from the liquid bath, agitating means positioned adjacent said cooling means, refrigerant circulating means positioned below said cooling means and said agitating means, refrigerant conduits, 10 said conduits extending exteriorly of said enclosure and connecting said cooling means to said refrigerant circulating means, and means operatively connecting said agitating means to said refrigerant circulating means. 15

13. Refrigerating apparatus, including an insulated enclosure containing a liquid heat transfer bath, cooling means positioned for absorbing heat from the liquid bath, agitating means positioned adjacent said cooling means, refrigerant circulat- 20 ing means positioned below said cooling means and said agitating means, refrigerant conduits, said conduits extending exteriorly of said enclosure and connecting said cooling means to said refrigerant circulating means, and means opera- 25 tively connecting said agitating means to said refrigerant circulating means, said cooling and agitating means being removable from said enclosure without disconnecting said conduits.

HERMAN J. DICK.

ROBERT E. FLEMING.
